HENRY W. MATHER, OF ROSEVILLE, NEW JERSEY.

PAPER-ROLL FOR MANIFOLDING SALES-PADS.

SPECIFICATION forming part of Letters Patent No. 642,799, dated February 6, 1900.

Application filed May 22, 1899. Serial No. 717,679. (No model.)

To all whom it may concern:

Be it known that I, HENRY W. MATHER, a citizen of the United States, residing at Roseville, in the county of Essex and State of New Jersey, have invented certain new and useful Improvements in Paper-Rolls for Sales-Pads, of which the following is a specification.

This invention relates to paper-rolls for sales-pads wherein the roll comprises a plurality of record-strips of equal width superposed and rolled up together, each record-strip being composed of individual sales-checks marked or numbered consecutively. In this class of devices it has been found difficult to employ a single roll of superposed record-strips of uniform widths, for the reason that in rolling them up the strips will not maintain their register, so that the sales-check of one strip will register with the correspondingly numbered check on the other strips. To overcome this difficulty, various means have been devised whereby similarly-printed record-strips perforated between the sales-checks could be brought to register; but, so far as I am aware, none of these have proved satisfactory. The present invention overcomes this difficulty in a simple manner and provides also record-strips of different-colored paper for the different departments of the store to which the sales-checks are to be distributed.

In the accompanying drawings, which illustrate an embodiment of the invention, Figure 1 is a perspective view of the paper-roll, and Fig. 2 shows the same partly unrolled. Fig. 3 is an illustrative view showing how the auxiliary colored record-strips are marked to correspond with the main strip. This view represents the strips displaced in a manner to show parts of auxiliary strips below the main strip.

P represents the paper-roll ready for use. This roll consists of a main record-strip A, divided or partitioned by suitable transverse markings into sales-checks *a*, (designated successively by consecutive characters and numbers, one or both, as D' D² D³, &c.) Usually these sales-checks will be printed to form a convenient blank suitable for being filled up by the salesman, and the line of division may be at *y* in Fig. 1.

The auxiliary record-strips B and C will

be, by preference, of colored paper—B being red, for example, and C being blue. They may be, of course, of any desired colors or 55 tints or quality of paper, and any number of them may be used, although only two are shown; but whatever may be the number of these auxiliary strips used they will all be of different colors. They will not have any 60 transverse markings indicating the end limits of the sales-checks, such as are seen on the strip A, and no transverse lines of perforations or indentations to fix such limits, as it is not material with my roll that the sales- 65 checks of the auxiliary strips shall have definite end limits; but each of the sales-checks of the colored auxiliary checks will be marked with the same characters or numbers as the sales-check corresponding to it on the strip 70 A, as D' D² D³, &c. The marks on these colored strips (seen at *b* in Fig. 3) may be so spaced as to fall about the middle of the sales-check, so that the taking up of the strips in rolling them up will not shift said marks 75 off from that portion of the auxiliary strip which goes to form the sales-check bearing that number. This construction and arrangement obviate the necessity of a special arrangement and registration of the superposed 80 strips in rolling them up and the necessity of friction devices for keeping the lines of severance of the several superposed strips in accurate register. Suppose, for example, that the record-strip is three and one-half inches 85 wide and the sales-check *a* is five inches long (which are convenient proportions) and that the outer record-strip on the roll is taken up in its entire length about one inch more than the inner strip. It follows that if the markings *b* on the auxiliary colored strips are placed five inches apart and that one at the inner end of the strip so placed as to come about opposite to the middle of the end sales-check *a* the markings *b* will always appear at 90 some point on the sales-checks severed from the colored auxiliary record-strips.

The sales-checks will be cut or severed from the record-strips without the aid of perforations or weakened transverse lines, and the 100 checks of the different colors will go to the different departments in the store to which they severally belong. The letter, as "D," may indicate the sales-department, and the

number identifies the check, with its multiples. The numerals and marks, as "D 16," on all the auxiliary strips register with some part of the sales-check of the main innerstrip 5 of the roll which bears the same numeral and letter.

I have spoken of the main strip A as the "inner" strip on the roll, for the reason that it is customary to place it on the inside, as 10 shown in the drawings; but obviously the strips may as well be rolled so as to place this strip A on the outside, and the word "inner," as applied to said strip herein, is only used in a descriptive sense and not as limiting 15 me to this. In the same way also I have referred to the markings b on the auxiliary strips as corresponding to the markings on the main strip, and they will ordinarily correspond in all respects; but it is only essential 20 that the strips shall have corresponding identifying marks or numbers. If numbers are used to identify, these numbers will correspond. If letters are used, the letters will correspond.

25 It may be proper to state that these paper-rolls are designed for use in connection with interleaved carbon-sheets in a casing or box of a known kind to be drawn out over a pad usually called a "sales-pad." Ordinarily the 30 strips A, B, and C will be of substantially equal width; but it may be desirable in some cases to make one or more of the auxiliary strips of lesser width than the main strip for the convenience of the user of the roll.

35 Having thus described my invention, I claim—

1. A paper-roll for sales-pads, composed of a plurality of superposed, rolled, record-strips, comprising a main record-strip A, divided by 40 transverse markings into sales-checks a, said checks being numbered and marked consecutively as described, and one or more unper-

forated, auxiliary record-strips, each of such auxiliary strips having printed on it consecutive numbers corresponding to those on the 45 main strip A, said numbers on the auxiliary record-strip being spaced to correspond to the length of the sales-checks a and each situated, before rolling, so far below the inner end of the sales-check that the maximum 50 amount of the strip taken up by creeping in forming the roll from the strips, will not shift said numbers off from that portion of the strip which goes to form the sales-check designed to bear that number, substantially as 55 set forth.

2. A paper-roll for sales-pads, composed of a plurality of superposed, rolled, record-strips, comprising a main record-strip A, divided by transverse markings into sales-checks a, said 60 checks being numbered and marked consecutively as described, and unperforated, auxiliary record-strips, B and C, of different colors, each of such colored strips having printed on it consecutive numbers corresponding to the 65 numbers on the strip A and separated by spaces equal to the length of the sales-checks a, said numbers on the auxiliary strips being situated, before rolling, so far below the inner ends of the respective sales-checks that 70 the maximum amount of the strips taken up by creeping in forming the roll from the same, will not shift said numbers off from those portions of the strips which go to form the sales-checks designed to bear those numbers, 75 substantially as set forth.

In witness whereof I have hereunto signed my name, this 20th day of May, 1899, in the presence of two subscribing witnesses.

HENRY W. MATHER.
